UNITED STATES PATENT OFFICE.

SYLVESTER ALEXANDER WATKINS, OF LONDON, ENGLAND, ASSIGNOR TO THOMAS TOWNSEND RUSSELL, OF LIVERPOOL, ENGLAND.

CLICK OR DETENT.

1,380,027.

Specification of Letters Patent. Patented May 31, 1921.

Application filed October 19, 1920. Serial No. 418,083.

To all whom it may concern:

Be it known that I, SYLVESTER ALEXANDER WATKINS, subject of the King of Great Britain, residing at London, in the 5 county of Middlesex and Kingdom of England, have invented a certain new and useful Click or Detent, of which the following is a specification.

This invention has reference to clicks or 10 detents for engaging the spaces between the teeth of wheels to prevent their recoil. It has been more particularly designed for use in connection with the winding gear of watches and clocks, though it is applicable 15 for other purposes.

Such clicks or detents have usually been kept to their work by a spring in the case of 20 watches, or sometimes by gravitation in the case of other kinds of mechanism, and the 25 object of the present invention is to provide an improved click or detent in which gravitation or the use of a throw-in spring is not relied on to keep it to its work, thus avoiding the disadvantages which accrue in the 30 event of such throw-in spring breaking or failing to act.

The improved click or detent constituting 35 the present invention comprises a rocking member so shaped with a detent end and a tail end, and pivoted at a suitable point between the two ends, that when the detent end rises from a tooth by the wheel being 40 revolved in one direction, the tail end is brought into such a position relative to the wheel that an on-coming tooth will lift it, and so depress the detent end as to cause it 45 to take hold of the next tooth to prevent backward motion of the wheel.

The invention will be understood from the 50 following description, reference being had to the accompanying drawings in which:—

Figures 1 and 2 are side elevations of the winding wheel of a watch and its click or detent, Fig. 1 showing the detent in action 55 and Fig. 2 showing the detent rising over the point of a tooth.

Figs. 3 and 4 are similar views showing a slight modification.

Referring first to Figs. 1 and 2, the improved click or detent comprises a two armed member A B so pivoted at C at or near mid-length that it is capable of being rocked or oscillated. One arm A which projects forwardly has a head or nose piece 60 such as a which engages any of the inter-

dental spaces in the toothed winding wheel D to form a detent to prevent recoil of the said wheel, and the other arm B forms a tail piece which is raised clear of the teeth of the said wheel when the detent is in engagement with a tooth as shown in Fig. 1. When however the wheel is revolved in the direction of the arrow, and the click or detent arm A of the two armed member rises over a tooth, the tail piece B is thereby 65 rocked toward the wheel D, and the end of the said tail piece enters between two teeth as shown in Fig. 2. Its entry between two teeth is sufficient to insure that an on-coming tooth will lift the tail piece B and so cause 70 the click or detent a to return and take into the next interdental space. One arm or other is therefore always in contact with the wheel, because when the detent arm A rises to slip over a tooth, the other arm is brought 75 against the teeth, so that the arms A, B act alternately, and the action is such that the slightest recoil of the wheel A will tend to cause the detent a to penetrate to the full depth of a tooth, and hold it down by the 80 pressure which the wheel exerts, thus obviating entirely the necessity of a throw in spring. The end of the tail piece is rounded or chamfered so that it will readily ride over an on-coming tooth. The pivotal hole 85 in the two armed member A B which is mounted on the shoulder screw C may be a round hole, or an elongated one. A banking pin E may be provided if desired to limit the oscillation of the detent. 90

The arrangement shown in Figs. 3 and 4 is similar, the principal modification being that the arm A of the pivoted two armed member has a supplementary head or nose piece a' at a short distance to the rear of the main head or detent a that is to say nearer the pivot C. The main head or nose piece a forms the click or detent as shown in Fig. 3, and the object of providing the second head or nose piece a' is to insure positive action. An on-coming tooth as shown in Fig. 4 lifts the tail piece B and depresses the arm A so that the nose piece a' partly penetrates an interdental space, and the slightest recoil of the wheel D brings a 105 tooth against this nose piece a' and so causes the detent a to penetrate the full depth of a tooth, and be held down therein by the pressure which the recoil of the wheel exerts, as shown in Fig. 3. 110

I declare that what I claim is:—

1. A click or detent comprising a rocking beam, a pivot for said rocking beam, a detent arm and a tail arm on said beam, both of greater radial length from said pivot than the distance between said pivot and the wheel to be controlled, and means to maintain the end of at least one of said arms in contact with the wheel.
- 10 2. A click or detent comprising a rocking beam, a pivot for said beam, a riding tooth on one side of said pivot at a greater radial distance from said pivot than the distance from the pivot to the wheel, means to prevent said riding tooth from locking the wheel in either direction of rotation, a feeding tooth on the beam at the opposite side of said pivot and means to maintain at least one of said teeth at any time in contact with the wheel.
- 15 3. A click or detent comprising a rocking beam, a pivot for said beam, a riding tooth on one side of said pivot at a greater radial distance from said pivot than the distance from the pivot to the wheel, means to prevent said riding tooth from locking the wheel in either direction of rotation, a feeding tooth on the beam at the opposite side of said pivot and at a greater radial distance from said pivot than the distance of the said pivot from the wheel, and means to maintain at least one of said teeth at any time in contact with the wheel.
- 20 4. A click or detent comprising a rocking beam, a pivot for said beam, a riding tooth on one side of said pivot at a greater radial distance from said pivot than the distance from the pivot to the wheel, means to prevent said riding tooth from locking the wheel in either direction of rotation a feeding tooth on the beam at the opposite side of said pivot, means to maintain at least one of said teeth at any time in contact with the wheel and a stop abutment on said beam at a greater radial distance from the pivot to the said beam than the distance of the wheel from the said pivot.
- 25 5. A click or detent comprising a rocking beam, a pivot for said beam, a riding tooth on one side of said pivot at a greater radial distance from said pivot than the distance from the pivot to the wheel, means to prevent said riding tooth from locking the wheel in either direction of rotation, a feeding tooth on the beam at the opposite side of said pivot and means to maintain at least one of said teeth at any time in contact with the wheel.
- 30 6. A click or detent comprising a rocking beam, a pivot for said beam, a riding tooth on one side of said pivot at a greater radial distance from said pivot than the distance from the pivot to the wheel, means to prevent said riding tooth from locking the wheel in either direction of rotation, a feeding tooth on the beam at the opposite side of said pivot and a banking pin to maintain at least one of said teeth at any time in contact with the wheel.
- 35 7. A click or detent comprising a rocking beam, a pivot for said beam, a riding tooth on one side of said pivot at a greater radial distance from said pivot than the distance from the pivot to the wheel, means to prevent said riding tooth from entering beyond the pitch circle line of the wheel to be controlled, a feeding tooth on the beam at the opposite side of said pivot and means to maintain at least one of said teeth at any time in contact with the wheel.
- 40 8. A click or detent comprising a rocking beam, a pivot for said beam, a riding tooth on one side of said pivot at a greater radial distance from said pivot than the distance from the pivot to the wheel, means to restrain the tail tooth to ride on the teeth of the wheel to be controlled only, a detent tooth on the said rocking member on the opposite side of the pivot and means to maintain at least one of said teeth permanently within the area swept out by the teeth of the wheel to be controlled.
- 45 9. A click or detent comprising a rocking beam, a pivot for said beam, a riding tooth on one side of said pivot at a greater radial distance from said pivot than the distance from the pivot to the wheel, means to restrain the tail tooth to ride on the teeth of the wheel to be controlled only, a detent tooth on the said rocking member on the opposite side of the pivot and means to maintain at least one of said teeth permanently within the area swept out by the teeth of the wheel to be controlled.
- 50 10. A click or detent comprising a rocking beam, a pivot for said beam, a riding tooth on one side of said pivot at a greater radial distance from said pivot than the distance from the pivot to the wheel, means to restrain the tail tooth to ride on the teeth of the wheel to be controlled only, a detent tooth on the said rocking member on the opposite side of the pivot and means to maintain at least one of said teeth permanently within the area swept out by the teeth of the wheel to be controlled.

from the pivot to the wheel, means to prevent said riding tooth from locking the wheel in either direction of rotation a feeding tooth on the beam at the opposite side of said pivot, means to maintain at least one of said teeth at any one time in contact with the wheel and a stop abutment on said beam engaging in a tooth space of the said wheel and at a greater radial distance from the pivot to the said beam than the distance of the wheel from the said pivot.

6. A click or detent comprising a rocking beam, a pivot for said beam, a riding tooth on one side of said pivot at a greater radial distance from said pivot than the distance from the pivot to the wheel, means to prevent said riding tooth from locking the wheel in either direction of rotation, a feeding tooth on the beam at the opposite side of said pivot and a banking pin to maintain at least one of said teeth at any time in contact with the wheel.

7. A click or detent comprising a rocking beam, a pivot for said beam, a riding tooth on one side of said pivot at a greater radial distance from said pivot than the distance from the pivot to the wheel, means to prevent said riding tooth from entering beyond the pitch circle line of the wheel to be controlled, a feeding tooth on the beam at the opposite side of said pivot and means to maintain at least one of said teeth at any time in contact with the wheel.

8. A click or detent comprising a rocking beam, a pivot for said beam, a riding tooth on one side of said pivot at a greater radial distance from said pivot than the distance from the pivot to the wheel, means to restrain the tail tooth to ride on the teeth of the wheel to be controlled only, a detent tooth on the said rocking member on the opposite side of the pivot and means to maintain at least one of said teeth permanently within the area swept out by the teeth of the wheel to be controlled.

In witness whereof I have hereunto signed my name this 6 day of Oct., 1920, in the presence of two subscribing witnesses.

SYLVESTER ALEXANDER WATKINS.
